UNITED STATES PATENT OFFICE.

LOUIS SHLEPP, OF NEW YORK, N. Y.

CIGAR-HOLDER AND ASH-RECEIVER.

1,145,808.

Specification of Letters Patent.

Patented July 6, 1915.

Application filed August 1, 1914. Serial No. 854,512.

To all whom it may concern:

Be it known that I, LOUIS SHLEPP, a citizen of the United States, and a resident of the city of New York, borough of Brooklyn, 5 in the county of Kings and State of New York, have invented a new and Improved Cigar-Holder and Ash-Receiver, of which the following is a full, clear, and exact description.

10 The object of the invention is to provide a new and improved cigar holder and ash receiver, arranged to allow one or more smokers to place their burning cigars in supporting position on the holder, to hold 15 the cigars against accidental displacement by gusts of wind or other causes especially when the device is used out of doors, and to permit of readily knocking off the cigar ashes and causing the same to drop into a 20 receptacle which can be conveniently emptied of its contents whenever it is desirable to do so.

Another object is to provide a cigar cutter for cutting off the cigar points and 25 dropping the cut-off portions into the receiving receptacle, and to provide means for readily disposing of the burned matches used for lighting the cigars.

In order to accomplish the desired result 30 use is made of a receiving receptacle on which is hinged a hood provided with a perforate cover or bottom overlying the said receptacle when the hood is in closed position, and cigar rests held on the said hood 35 and each adapted to support a cigar with the inner end, however, extending over the said perforate cover or bottom.

A practical embodiment of the invention 40 is represented in the accompanying drawings forming a part of this specification, in which similar characters of reference indicate corresponding parts in all the views.

Figure 1 is a perspective view of the cigar holder and ash receiver; Fig. 2 is a sectional side elevation of the same on the line 2—2 of Fig. 3; Fig. 3 is a sectional plan view of the same on the line 3—3 of Fig. 2; and Fig. 4 is a cross section of the cigar cutter, the section being taken on the line 4—4 of Fig. 3.

The base of the cigar holder and ash receiver is in the form of a receiving receptacle A open at the top and adapted to receive cigar ashes, the cut-off tops of cigars and burned matches, as hereinafter more fully explained. The upper edge of the receptacle A is connected by a hinge B with a

hood C normally forming a cover for the receptacle A and adapted to be swung into open position to permit of emptying the receptacle A of its contents whenever it is desirable to do so. The receptacle A is provided opposite the hinge B with a suitable locking device D for normally locking the hood C in closed position on top of the receptacle A. On the top of the hood C is mounted a match holder or a box E of any approved construction.

The hood C is provided in its lower portion with a perforate cover or bottom F, preferably in the form of wire netting extending across the top of the receptacle A at the time the hood C is in closed position, and in the center of the perforate cover F is erected a post G, preferably in the form of a cylinder of wire netting to permit the user of the device to knock off the ashes from the butt end of the burning cigar and to allow the said ashes to drop through the perforate cover F, into the receptacle A.

From the lower portion of the hood C project outwardly a number of spaced and horizontally disposed cigar rests H of trough-like shape, to readily support a cigar. The cigar rests H are preferably struck up from the material of the hood C to provide openings C' in the sides of the hood C and above the rests H for the passage of the butt end of a cigar into the interior of the hood C, as indicated in Figs. 1 and 2. The bottom of each cigar rest H is approximately in the same horizontal plane as the perforate cover F so that the latter forms practically a continuation of the several cigar rests H to support the inner portions of the cigars held on the rests H at the time. When the device is set on a table or other support and the hood C is locked in closed position then a number of burning cigars can be placed on the several rests H by a number of smokers seated at the table, and each smoker 100 can readily knock off the ashes either by contacting the same with the perforate cover F or the post G, the ashes in either case dropping down into the receptacle A.

On one side of the receptacle A is arranged a cigar cutter I, of any approved construction, but so arranged that the cut-off tips of the cigars drop into the receptacle A. The side of the receptacle A is further provided with an opening J through which 105 burned matches may be passed into the receptacle A.

In order to empty the receptacle A of ashes, cigar tips and burned matches, it is only necessary to unlock the hood C and then swing the hood C rearwardly into open position to permit of dumping the contents of the receptacle A into a pail or other vessel. The hood C is then again returned to closed position and locked in place on the cover A by the locking device D.

10 The cigar holder and ash receiver shown and described is very simple in construction and composed of comparatively few parts, not liable to get out of order easily.

Having thus described my invention, I claim as new and desire to secure by Letters Patent:

1. A cigar holder and ash receiver, comprising a receptacle, a cover hinged on the said receptacle and adapted to swing into open or closed position, the cover having a netting extending across the top of the said receptacle, and a series of radially disposed cigar rests on the said cover and extending outward beyond the edge of the cover, each cigar rest being adapted to support a cigar, the bottoms of the said cigar rests being approximately on the same level as the said netting so that the latter forms a continuation of the said cigar rests.

20 2. A cigar holder and ash receiver, comprising a receptacle, a cover for the said receptacle having a netting extending across the top of the said receptacle, a series of radially disposed cigar rests extending outwardly from the said cover, each for supporting a cigar, and a central perforate post erected on the said netting.

25 3. A cigar holder and ash receiver, com-

prising an ash receptacle, a hood hinged to the top of the said ash receptacle and provided at its bottom with a netting overlying the said ash tray, and a cigar rest projecting from the side of the hood at an opening in the hood and above the said netting to support a cigar and to allow the cigar ashes to drop through the netting into the said receptacle.

4. A cigar holder and ash receiver, comprising an ash receptacle, and a hood hinged to the top of the said ash receptacle and provided at its side with cigar rests projecting outwardly and struck up from the hood material to form openings in the side of the hood above the cigar rests for the passage of the butt ends of the cigars into the interior of the hood.

5. A cigar holder and ash receiver, comprising an ash receptacle, a hood hinged to the top of the said ash receptacle and provided at its side with cigar rests projecting outwardly and struck up from the hood material to form openings in the side of the hood above the cigar rests for the passage of the butt ends of the cigars into the interior of the hood, and a wire netting secured in the lower portion of the said hood and forming an extension for the said cigar rests.

In testimony whereof I have signed my name to this specification in the presence of two subscribing witnesses.

LOUIS SHLEPP.
